POWER FUSE

William D. Kyle, Jr., Milwaukee, and Anthony Van Ryan, South Milwaukee, Wis., assignors to Kyle Corporation, South Milwaukee, Wis., a corporation of Wisconsin

Application April 15, 1943, Serial No. 483,159

21 Claims. (Cl. 200—120)

1

This invention relates to improved power fuses, by which is meant fuses capable of rupturing successfully currents of very high amperage—our main purposes being to cure certain deficiencies which either characterize or have been found to obtain sporadically in fuses heretofore widely employed and designed for heavy duty service; and, in addition, to effect substantial monetary savings with respect both to initial costs and maintenance.

One of our objects is to devise an efficient power fuse in which is avoided the characteristic deficiencies of conventional liquid fuses, and wherein the fuse housing requires no liquid-tight seals.

Another object is to devise a power fuse which will quickly interrupt a heavy current while obviating all possibility of a leakage path of consequential proportions being established following a fuse operation.

Still another object is to provide a power fuse the operative condition of which can readily be determined by visual inspection, without dismantling.

A further object is to provide a power fuse which can easily be rehabilitated in the field at a cost which is but a fraction of that of an entire fuse assembly.

An additional object is to devise a power fuse which will blow without an accompanying violent explosion and, therefore, will neither burst nor produce an objectionably loud report, nor give off objectionable fumes or become hot on being left in the circuit.

One embodiment of our invention is depicted in the drawing, wherein:

Fig. 1 is a longitudinal sectional view of a complete fuse assembly, exclusive of the mounting structure therefor;

Fig. 2 is a longitudinal sectional view of a fuse insert or cartridge constituting a replaceable component of the fuse assembly and a constituent part of the fuse-link;

Fig. 3 is an elevational view of the fuse assembly, drawn to a smaller scale than Fig. 1;

Fig. 4 is a cross-sectional view taken along line 4—4 of Fig. 2;

Fig. 5 is a cross-sectional view taken at line 5—5 of Fig. 2; and

2

Fig. 6 is a cross-sectional view taken at line 6—6 of Fig. 2.

The entire fuse assembly, as shown in each of Figs. 1 and 3 is a self-contained unit adapted to be withdrawably mounted on a suitable support, not shown, having the usual line terminals and spring clips or other attachment means by virtue of which the fuse assembly can easily and quickly be mounted. Fuse mounts of that nature being thoroughly familiar to those who are concerned with this art, it is thought unnecessary to illustrate an example thereof in the present application.

The fuse shown includes a housing 1 in which is enclosed a fuse-link comprising a fuse cartridge or insert 2, together with a helical retracting spring 3 and a flexible conductor 4 which shunts the spring and is connected at its lower end to the fuse cartridge and anchored at its upper extremity to the housing.

The housing comprises a transparent glass or transparent plastic tube 5, for example, "Lucite," which is made long enough, at least, to secure the requisite spacing between its metal-capped ends whereby to ensure against arcing-over following a fuse blowout. Attached to the upper end of tube 5 is a metal ferrule 6—this being firmly secured to the tube by cement or fusible metal, as indicated at 7. Ferrule 6 is designed to engage suitable terminal clips, not shown, by means of which the fuse assembly is mounted. The design of this ferrule, as well as the lower ferrule, to be described later, is, of course, adaptable to accommodate whatever style of mounting it may be thought best to employ.

The upper end of ferrule 6 is threaded externally at 8 to receive a metal cap 10 which serves both as a removable closure for the upper end of the housing and as means for clamping in place and making good electrical contact with a button-like member 11 which forms the upper terminal of the fuse-link assembly comprising parts 2, 3, and 4, in addition to other parts described hereinafter.

To the lower end of tube 5 is secured a second metal ferrule 12. This is designed to accommodate a mounting clip and is threaded externally at 14 to receive a removable cap 15 having a number of openings 16 through which the fluids incidental to the blowing of the fuse can dis-

charge freely into the surrounding atmosphere. Cap 15 functions as a receptacle to catch the detached fuse parts which drop down when the fuse blows, and, conjointly with ferrule 12, to grip the flexible leaders of the fuse cartridge and thereby establish electrical connection between ferrule 12 and the lower terminal of the fusible section, as presently will be described.

The fuse-link assembly comprises cartridge or insert 2 (detailed in Figs. 2, 4, and 5), retracting spring 3, flexible conductors 4, of which two are shown in parallel, and the button-like terminal member 11. The upper end of the cartridge is detachably connected to the lower end of spring 3 and to the lower end of conductors 4 through the medium of a conductive member 17.

Fuse cartridge 2 (see Figs. 2, 4, and 5) comprises a metal sleeve 18 which is reduced in external diameter at its upper end and externally threaded at 19 to engage a corresponding internal thread in member 17. This serves to anchor the upper end of the cartridge to member 17 and, in turn, to spring 3 and flexible conductors 4. Sleeve 18 is internally threaded at 20 to engage a non-conductive tube 21 which may be made of horn fiber; and said sleeve has an internal shoulder at 18a which co-operates with the upper end of tube 21 to grip the external flange 22a of a metal insert 22 which is bored to form a conically tapered seat for the frustoconical lower end of a sheet metal receptacle or capsule 23 in which is stored under pressure a suitable arc-extinguishing gas. Capsule 23, which may be a commercial soda water bottle charging unit filled with carbon dioxide, and commonly known as a Sparklet bulb, is held in its seat by means of a metal disc 24 which presses against the upper end thereof and is locked in place by ears 18b which are bent over the peripheral edge of the disc. The lower end of capsule 23 is closed by means of a thin metal disc 23a which is adapted to be punctured quickly when subjected to an arc impinging thereon. Puncturing said disc releases the enclosed gas.

Situated immediately below insert 22 and supported on an internal shoulder 21a formed in tube 21 is a nozzle member 25 having a bore which is conically flared at 25a and straight at 25b. The straight portion of the bore is diametrically constricted, as shown, in order to form a confined passageway immediately below the lower end of capsule 23, in which passageway the gas discharged from the capsule can be concentrated on the arc which forms when the fuse blows. Sleeve 21 is made, preferably, of refractory, non-gas-evolving material such as porcelain or "lava."

The bore diameter at 25b should be smaller than the outside diameter of the neck forming the lower end portion of capsule 23 so that the arc will invariably be concentrated on the aforementioned disc. If the arc is not thus directed, but, instead, is permitted to wander, there may be undue delay or even failure to puncture the receptacle. Hence, the aforementioned bore diameter is a critical factor and constitutes one of the features of this invention.

Metal insert 22 is slotted externally and axiswise at two diametrically opposite sides, the slots being identified by reference numerals 22b and 22c respectively. Slot 22c receives the upper end of a fuse wire 26, which is soldered in place therein; and slot 22b receives the upper end of a strain wire 27 which similarly is soldered in said slot and is threaded through an aperture 22d from the

bore of insert 22. Sectional view Fig. 4, considered in conjunction with Fig. 2, shows clearly the slots 22b and 22c and the disposition of strain and fuse wires, respectively, therein. Said strain and fuse wires pass downwardly through narrow cross-slots 25d and thence through constricted bore 25b and into the flared passageway 25a where they are connected at their lower ends to a solderless compression connector 28. Cross-slots 25d are shown most clearly in Fig. 6 wherein the fuse and strain wires have been omitted for the sake of clarity.

To prevent the fuse and strain wires being twisted there is secured to connector 28 a washer 29 having oppositely disposed up-turned peripheral ears 29a and 29b (see especially Fig. 5) which are seated in corresponding notches 25c formed in the lower end of nozzle member 25. Thus washer 29 is restrained against rotation and, in turn, serves to prevent rotation of connector 28 and the fuse and strain wires.

Attached to connector 28 and depending therefrom are two parallel, stranded, flexible conductive leaders 30, 31 which, as shown in Fig. 1, are intended to be clamped between lower ferrule 12 and lower cap 15—the ferrule being slotted at 12a and 12b to provide recesses for accommodating the flexible leaders.

Normally the fuse cartridge is anchored down in its lowermost position by the clamping of flexible leaders 30, 31. This puts spring 3 under tension and, accordingly, biases the cartridge toward movement upwardly, which movement normally is prevented by strain wire 27. When the latter is severed, concurrently with the blowing of the fuse wire, the cartridge is quickly drawn up by spring 3—thereby effecting an abrupt separation of the fuse wire and strain wire terminals and a consequent stretching out of the arc. Blowing of the fuse wire and incidental severance of the strain wire, as well as the fuse wire, on either an overload or short circuit causes an arc to form within the constricted passageway 25b. The upper end of the arc is instantly transferred to the lower end of capsule 23, and the thin disc 23a is immediately punctured so that the gas therein is released in the form of a high velocity jet or blast which impinges directly upon the arc. All this occurs within a fraction of a cycle after the fuse wire blows, and at the same time the arc is being rapidly lengthened by virtue of the upward movement of the cartridge. The deionizing effect of the gas coupled with rapid elongation of the arc gap generally results in extinguishing the arc at the first current zero following severance of the fuse wire.

Because nozzle member 25 is made of an inert material which does not evolve gas in substantial quantities when subjected to the temperature of an arc, it follows that blowing of the fuse is not accompanied by a loud report, and no great amount of pressure is developed such as would be apt to burst the cartridge or the housing.

Fiber tube 21 does, no doubt, evolve some gas; but its inside diameter is relatively large and its exposed internal surface is both short and of small area. Hence no great amount of pressure is engendered by reason of the fiber tube.

When the fuse has blown and cartridge 2 has moved upwardly under the retractile force of spring 3, there is no medium intervening the severed ends of the fusible section which, by reason of carbonization, could present a substantial leakage path. This follows from the fact that tube 5, whether of glass or Lucite, is not sus-

ceptible to carbonization and provides no conductive surface; and the use of these materials is made possible by the avoidance of bursting pressures. This is an important feature in a power fuse and one which is inherent in the illustrated fuse structure and entails no added cost.

As will be self-evident, it is a very simple matter to withdraw the entire fuse-link from the housing and to detach the cartridge from member 11. Hence, the cartridge can readily be replaced in the field by a service man; and the cost of a replacement cartridge is a relatively small part of the cost of the entire fuse assembly.

Inasmuch as extinguishment of the arc is not dependent upon evolution of gas, the volume and expulsive action of which is predicated upon the intensity of the arc, it follows that an arc of low current value is extinguished just as readily as a heavy current arc; and no special provision has to be made for extinguishing low-intensity arcs as must be done in some other types of power fuses. Here the volume of arc-extinguishing gas and the force of its discharge is constant, irrespective of the intensity of the arc.

What is claimed is:

1. In a fuse, the combination with a fusible section having an anchored terminal and a movable terminal, of spring means for abruptly moving the movable terminal of said fusible section away from the anchored terminal upon severance of said fusible section, a source of arc-extinguishing gas under pressure adjacent the movable terminal and movable therewith, means operative in response to an arc resulting from the severance of said fusible section for releasing said gas immediately adjacent said arc concurrently with the separation of said terminals by said spring means, and a passageway for directing said gases into the path of said arc.

2. In a fuse, a cartridge including a gas-filled receptacle, a fusible section enclosed within said cartridge, one terminal of said fusible section being attached to said cartridge and the other terminal thereof being anchored otherwise than by attachment to said cartridge, a spring operative to move said cartridge away from the anchorage of said other terminal and effective to separate said terminals abruptly upon severance of said fusible section, and means for releasing the gas from said receptacle into the space within said cartridge traversed by the arc which results from blowing said fusible section, said means being operative to release the gas as aforesaid concurrently with the separation of said terminals by said spring means.

3. A fuse-link comprising a fusible section, means for anchoring one end of said fusible section, spring means for retracting the other end of said fusible section upon blowing of the fuse whereby abruptly to elongate the arc which is formed between the terminals of the fusible section, a source of arc-extinguishing gas under pressure disposed in operative relation to the space in which said arc is formed, and means responsive to the arc for releasing the gas from said source into said space to assist in the extinguishment of said arc supplementally to and concurrently with the arc-extinguishing action of said spring means, said spring biasing said source in the direction of retraction of said other end.

4. The combination in a fuse-link of a cartridge enclosing a conductive receptacle filled with

arc-extinguishing gas under pressure, a fusible conductor disposed within said cartridge adjacent one end of said receptacle and so arranged relative thereto that on blowing of the fusible conductor the resultant arc is in series circuit with said receptacle, one end only of said fusible conductor being anchored to said cartridge, the other end of said fusible conductor being arranged to be attached to an anchorage extraneous the fuse-link, the disposition of said fusible conductor relatively to said receptacle being such that the arc which results from blowing of the fusible conductor will quickly puncture said receptacle and thus release therefrom a jet of gas directed at the arc, and a spring for biasing said cartridge toward movement in a direction effective to separate the severed terminals of said fusible conductor following a blowout.

5. The combination in a fuse-link of a cartridge comprising a metallic sleeve, a tube of insulating material detachably connected to and depending from said sleeve and co-axial therewith, a removable receptacle filled with arc-extinguishing gas under pressure disposed within said sleeve, a nozzle member of non-gas-evolving non-conductive material disposed within said tube immediately below said receptacle and having a constricted passageway immediately adjacent the lower end of said receptacle, a fuse wire and a strain wire in parallel extending through said constricted passageway and each anchored at its upper end to a part of the cartridge structure, a flexible conductive leader connected at one end to the lower ends of said strain wire and fuse wire, a tension spring detachably connected to the upper end of said cartridge for biasing said cartridge upwardly, and means operative in response to an arc resulting from the severance of said fuse wire for releasing said arc extinguishing gas.

6. The combination in a fuse-link of a cartridge comprising a metallic sleeve, a retracting spring detachably connected to the upper end of said metallic sleeve, a tube of insulating material detachably connected to and depending from the lower end of said metallic sleeve and co-axial therewith, a metallic insert within said cartridge and secured between said sleeve and tube jointly, said insert having a conically tapered bore, a gas container within the bore of said sleeve and seated at its lower end in the conically tapered bore of said insert, a nozzle member of non-conductive, non-gas-evolving material disposed within said tube immediately below said metallic insert and having a constricted axial passageway immediately below said gas container, a strain wire and a fuse wire each connected at its upper end to said metallic insert and extending downwardly through said constricted passageway, a flexible conductive leader connected at one end to the lower ends of said fuse wire and strain wire and extending outwardly from the lower end of said cartridge, a terminal member attached to the upper end of said spring, a flexible conductor extending axially through said spring and electrically interconnecting said terminal member with said metallic sleeve, and means operative in response to an arc resulting from the severance of said fuse wire for releasing said gas immediately adjacent said arc.

7. The combination in a fuse-link of a tubular cartridge, a receptacle containing arc-extinguishing gas under pressure disposed within said cartridge, a nozzle member made of substantially non-gas-evolving, non-conductive material having a

constricted axial passageway immediately adjacent and below said receptacle, a fuse wire extending through said passageway and anchored at its upper end above said passageway, the lower end of said fuse wire being provided with means for effecting anchorage thereof extraneously of said cartridge, a retractile spring connected to the upper end of said cartridge for moving said cartridge lengthwise to effect abrupt separation of the terminals of the severed fuse wire when a blowout occurs, and means operative in response to an arc resulting from the severance of said fuse wire for releasing said arc extinguishing gas immediately adjacent said arc concurrently with the separation of said terminals by said spring.

8. The combination in a fuse of structure including a receptacle containing arc-extinguishing gas under pressure, said receptacle having a portion constituting an alternate arc electrode, said portion being quickly perforable by the arc when caused to operate as an arc electrode, a fusible element having one terminal only electrically connected with said receptacle, means for effecting electrical connection with and for anchoring the other terminal of said fusible element, said portion being so positioned with respect to the terminals of said fusible element that after a blowout has occurred the shortest arc path is between said portion and said other terminal, and spring means for biasing the terminals of said fusible element apart to effect abrupt separation thereof when a blowout occurs.

9. The combination in a fuse, of a tubular cartridge, a receptacle containing arc-extinguishing gas under pressure, said receptacle being disposed within said cartridge, a conductive member situated within said cartridge and bored axially to form a seat for said receptacle, the lower portion of said receptacle projecting downwardly through and beyond said conductive member, a non-conductive member situated below said receptacle and said conductive member and having a constricted bore which is obstructed at one end by the lower end of said receptacle, a fuse wire and a strain wire in parallel and each connected at its upper end to said conductive member, said wires both extending downwardly through said constricted bore and connected at their lower ends to conductive means anchored extraneously of said cartridge, and means operative in response to an arc resulting from the severance of said fuse wire for releasing said arc extinguishing gas immediately adjacent said arc.

10. The combination in a fuse, of a tubular transparent housing, and a tensioned fuse-link within said housing and comprising a tensioned coil spring and a fuse cartridge detachably connected in series, one end of said spring being anchored to one end of said housing, said cartridge including a tubular metallic sleeve detachably connected serially and coaxially with a tube of insulating material, a conductive member within said cartridge, said conductive member being gripped between said metallic sleeve and said tube and having a frusto-conical bore, a receptacle disposed within said metallic sleeve and containing arc-extinguishing gas under pressure, said receptacle being generally cylindrical in form and having an attenuated neck portion at one end which seats in said frusto-conical bore and projects through and beyond said conductive member, a nozzle member of refractory material disposed within said tube and immediately adjacent said conductive member, said nozzle

8
zle member having a constricted bore terminating at one end immediately adjacent the end of said neck portion, a fuse wire and a strain wire in parallel, each connected at one end to said conductive member and extending through said constricted bore, a flexible conductive leader connected to the other ends of said fuse and strain wires, said leader being anchored to said housing and serving conjointly with said strain wire to maintain said fuse-link under tension and means operative in response to an arc resulting from the severance of said fuse wire for releasing said arc extinguishing gas.

11. In a fuse, the combination with a fusible section having an anchored terminal and a movable terminal, of spring means for abruptly moving the movable terminal of said fusible section away from the anchored terminal upon severance of said fusible section, a source of fluid arc-extinguishing material under pressure adjacent the movable terminal and movable therewith, means operative in response to an arc resulting from the severance of said fusible section for releasing said material immediately adjacent said arc concurrently with the separation of said terminals by said spring means, and a passageway for directing said arc extinguishing material into the path of said arc.

12. A fuse cartridge constituting a replaceable component of a fuse-link and comprising: a conductive sleeve having a lengthwise-extending bore, a tube of non-conductive material co-axial with and in end-to-end threaded engagement with said sleeve and detachable therefrom, a metal insert disposed within one end portion of said sleeve and co-axial with said sleeve, said insert being secured in place by said tube and removable from said sleeve after detaching said tube from said sleeve, said insert forming, in conjunction with the bore of said sleeve, a chamber, a gas-filled capsule disposed within said chamber, said insert being bored through axially and formed to provide a seat for one end of said capsule, a nozzle member of refractory material secured within said tube adjacent said insert and having a constricted axial passageway terminating immediately adjacent one end of said capsule, a flexible conductive leader, a fusible member connected at one end to said insert and at the other end to said flexible leader, said fusible member extending through said constricted passageway, and means operative in response to an arc resulting from the severance of said fusible member for releasing said gas immediately adjacent said arc.

13. A fuse cartridge constituting a replaceable component of a fuse-link and comprising: a conductive sleeve having a lengthwise extending bore, a tube of non-conductive material co-axial with and in end-to-end threaded engagement with said sleeve and detachable therefrom, a metal insert, said sleeve being counterbored at the end adjacent said tube to receive said insert, the latter being clamped in place by said sleeve and tube conjointly, a gas-filled capsule disposed within a chamber formed by said sleeve bore and said insert, the latter being bored to form a seat for one end portion of said capsule and to form a passageway through which one end of said capsule projects, a nozzle member of refractory material secured within said tube adjacent said insert and having a constricted axial passageway terminated at one end by the aforementioned end of said capsule, a conductive leader, a fuse wire and a strain wire, said wires being connected

each at one end, respectively, to said insert and at their other ends to said conductive leader, said wires extending through said constricted passageway, and means operative in response to an arc resulting from the severance of said fuse wire for releasing said gas immediately adjacent said arc.

14. A fuse cartridge constituting a replaceable component of a fuse-link and comprising: a gas-filled capsule, a conductive sleeve bored lengthwise to form a chamber for the reception of said capsule, a disc secured in one end of said bore and in pressing engagement with one end of said capsule, a metal insert removably seated within said sleeve remotely from said disc and forming one terminus of said chamber, said insert being bored to form a seat for said capsule and to form a passageway through which the other end of said capsule projects, a tube of non-conductive material co-axial with and in end-to-end threaded engagement with said sleeve, and detachable therefrom, said insert being clamped in place by said sleeve and tube conjointly, means within said tube defining a constricted passageway in direct communication with said other end of said capsule, a conductive leader, a fuse wire and a strain wire, said wires being connected each at one end, respectively, to said insert and at their other ends to said conductive leader, said wires extending through said constricted passageway, and means operative in response to an arc resulting from the severance of said fuse wire for releasing said gas immediately adjacent said arc.

15. A refill fuse link unit for fuse cartridges, said unit comprising a metal sleeve having terminal connecting means at one end, an insulating sleeve secured to and projecting from the other end of said metal sleeve, the end of said insulating sleeve remote from said metal sleeve being open, a receptacle in said metal sleeve containing a fluid under pressure and having a destructible seal in said insulating sleeve for releasing said fluid, means retaining said receptacle in said metal sleeve, a fusible section electrically connected at one end to said metal sleeve and positioned in said insulating sleeve, a flexible leader connected with the other end of said fusible section and projecting from the open end of said insulating sleeve, and means operative in response to an arc resulting from the severance of said fusible section for destroying said seal and releasing said fluid.

16. A refill fuse link unit for fuse cartridges, said unit comprising a metal sleeve having terminal connecting means at one end, an insulating sleeve secured to and projecting from the other end of said metal sleeve, said insulating sleeve being open at its end remote from said metal sleeve and having a nozzle like constriction flaring toward said open end, a receptacle in said metal sleeve containing a fluid under pressure and having a destructible seal adjacent said nozzle like constriction, a fusible section electrically connected at one end to said metal sleeve and projecting through said constriction, a terminal connecting conductor projecting from said open end and secured to the other end of said fusible section, and means operative in response to an arc resulting from the severance of said fusible section for destroying said seal and releasing said fluid.

17. An arc extinguishing unit comprising a metal sleeve having a terminal connecting means at one end, an insulating sleeve secured to and projecting from the other end of said metal

sleeve, a receptacle in said metal sleeve containing a fluid under pressure and having a destructible seal in said insulating sleeve for releasing said fluid, means retaining said receptacle in said metal sleeve, and conductor means extending from said open end for establishing an arc to said destructible seal on the occurrence of an abnormal condition in an electric line to which said unit may be connected.

18. An arc extinguishing unit comprising a metal sleeve having terminal connecting means at one end, an insulating sleeve secured to and projecting from the other end of said metal sleeve, said insulating sleeve being open at its end remote from said metal sleeve and having a nozzle-like constriction flared toward said open end, a receptacle in said metal sleeve containing a fluid under pressure and having a destructible seal adjacent said nozzle-like constriction, and conductor means extending from said open end for establishing an arc to said destructible seal on the occurrence of an abnormal condition in an electric line to which said unit may be connected.

19. In a fuse, a cylindrical receptacle containing arc-extinguishing fluid under pressure, said receptacle having a neck portion of reduced diameter at one end, the terminus of said neck portion being closed by means of a closure member of thin sheet metal, the exposed diameter of which is less than the outside diameter of said neck portion, a nozzle member of non-conductive material having a recess for the reception of said neck portion and a passageway co-axial with said recess and terminated at one end by said closure member, said passageway having a diameter not materially greater than the exposed diameter of said closure member, and a fusible member extending axially through said passageway and operative, on blowing, to strike an arc within said passageway adjacent said closure member, the arrangement being such that the arc will impinge upon said closure member in preference to other parts of said receptacle, thereby ensuring that said closure member will be quickly punctured.

20. In a fuse, a nozzle member of non-conductive material having a passageway therethrough, a receptacle containing arc-extinguishing gas under pressure, said receptacle having a discharge port which is normally closed by a closure member of conductive material which is capable of being quickly punctured by an arc impinging thereon, said passageway being terminated at one end by said closure member, said passageway being of a diameter, immediately adjacent said closure, not materially greater than the exposed diameter of said closure member, and fusible means capable of producing an arc within said passageway, the arrangement being such that said closure member will function as one electrode of said arc immediately after the arc is established.

21. An arc extinguishing unit comprising a metal sleeve having a terminal connecting at one end, an insulating sleeve secured to and projecting from the other end of said metal sleeve, a receptacle in said metal sleeve containing a fluid under pressure and having a destructible electrically conductive seal in said insulating sleeve for releasing said fluid, and a bored metal insert retaining said receptacle in said metal sleeve, in combination with a conductor including a fusible section adjacent the seal extending from said insert through the open end of said insulating

11

sleeve for establishing an arc to said destructible seal on the occurrence of an abnormal condition in an electric line to which said unit may be connected.
